UNITED STATES PATENT OFFICE.

HELGE A. BORRESEN, OF CHICAGO, ILLINOIS.

AUTOMOBILE BUMPER.

Application filed May 26, 1923. Serial No. 641,642.

The invention relates to automobile bumpers and has among its various objects the provision of a construction of this character which will yieldably resist impacts imparted to it upon its engagement with another object.

It is a feature of the invention to provide a construction which will offer a certain predetermined yieldable resistance to the initial force applied and to employ in the structure means which, after the predetermined elasticity has been reached, will be substituted for the yieldable resistance just referred to and thereafter present an element to the force applied which element has greater resisting qualities than that of yieldable resistance.

It is an object of the invention to employ an expansible element for resisting the initial force applied to the structure.

It is a further object to associate with the expansible element just referred to, a means which acts to limit the expansion of said element, and which when the elasticity of the expansible element is reached will be substituted for said expansible element and have the force applied thereto.

In addition it is an object to connect or associate this means, which is substituted for the expansible member, with another means to which the force will be transmitted through the medium of said means, the last mentioned means preferably also being of a resilient character which will thus present a yieldable resistance to the force applied.

It is another object of the invention to provide a bumper in which the elements whereby it is secured to the vehicle and the members which extend across the end of the vehicle are permitted to move relatively to each other when a force is applied to either of said elements or said members.

It is a feature of the invention to employ a plurality of devices each of which is capable of presenting a variable resistance to the force applied, and to connect these elements together, the connectors producing barriers which prevent the passage of an object between a pair of said plurality of elements.

In addition to the above it is an object to design the connectors above referred to so that one of the resistant elements may move with respect to another should a force be applied to the former.

It is also an object of the invention to provide a bumper with a guard and to arrange this guard at the juncture or connection of the means whereby the bumper is connected to the vehicle, and the members which extend across the end of the vehicle.

The invention has these and other objects all of which will be explained in detail and more readily understood when read in conjunction with the accompanying drawings which illustrate various arrangements of which the invention is susceptible, it being therefore obvious that changes and modifications may be resorted to without departing from the spirit of the invention as expressed in the appended claims forming a part hereof.

In the drawings, Figure 1 is a plan view of a bumper structure embodying the various features above referred to. Figure 2 is a front view of the structure illustrated in Figure 1. Figure 3 is a plan view of a modified form. Figure 4 is a front view of an end of the structure shown in Figure 3. Figure 5 is a side view of the structures shown in Figures 3 and 4. Figure 6 is a detail of a portion of the structure shown in Figures 3 to 5. Figure 7 is a side view of a structure such as that illustrated in Figures 1 and 2, showing a connector which may be employed to prevent the passage of an element between certain other portions of the structure. Figure 8 is a side view showing a guard element associated at the juncture of the means whereby the structure may be mounted upon the vehicle and certain guard elements. Figures 9 and 10 are respectively front and plan views of the structure shown in Figure 8. Figure 11 is a plan view of a modified means for connecting the bumper to the vehicle. Figure 12 is another modified arrangement showing a flat member for resisting the initial force applied to the bumper and having associated therewith a means for limiting the action of said force upon said member. Figure 13 is an enlarged end view of the structure shown in Figure 12. Figure 14 is a detail of a connector employed in the structure.

The structures illustrated in the drawings include a member provided to resist the initial force applied to the structure, an element which is substituted for said member to arrest forces in excess of those which

said member is capable of resisting and resilient means to which said element is attached which co-operate to yieldably resist the force applied to said element.

- 5 In the structure illustrated in Figures 1 and 2 resilient members 15, 16, 17 and 18 are employed which are arranged in pairs, and are respectively secured to the frame or chassis of the vehicle and provide supports for the various other portions entering into the bumper structure. These spring members are each formed so that they extend outwardly from the sides of the chassis and are then bent inwardly toward the chassis.
- 10 15 The inner ends of said spring members are each provided with a connector 19 whereby the cross members generally designated 20 and 21 are secured to the ends of the spring members 15, 16, 17 and 18.
- 15 20 In view of the fact that these connectors and the cross members are respectively of a similar construction, an explanation of the construction of one cross member and the method of attaching it to its respective
- 25 spring members such as 15 and 16 will suffice for an understanding of all.

The connector 19 employed in the present structure is shown in detail in Figure 14 and includes the tubular portion 22 through which the pin 23 is passed and has the flat apertured extension 24 whereby it may be secured to the end of one of the springs 15 to 18 by being riveted or otherwise fastened thereto.

- 30 35 The cross members 20 and 21 which extend across the end of the vehicle each have their opposite ends respectively attached to one of the spring members 15 to 18 through the medium of a connector 19. These cross members each include a coiled spring 25 which may normally be under a tension sufficient to present a yieldable resistance to an initial force applied thereto.

40 45 The connectors 19 are inserted into the open ends of these springs 25 and are suitably secured thereto at this point. A member 26, which in the present instance is illustrated as being a chain, is encased within the coils of these springs 25 and has its opposite ends each secured to the connectors 19 through the medium of the pin 23, which as before stated, is passed through the connector and through a link of said chain and thus will provide an attachment having the necessary strength to withstand the forces applied to this portion of the structure.

- 50 55 The chain 26, under normal conditions lies loosely within the spring 25 or in other words, is of a length which is greater than the length of the spring in which it is confined, providing slack, which will allow either of the springs 25 to be expanded to a certain degree upon the application of an initial force thereto, which force after
- 60 65 it exceeds the prescribed resistance of said

spring will be applied to the chain, which by virtue of its connection with the respective spring members 15, 16, 17 and 18 will transmit the force to said last mentioned springs, and offer a greater resilient resistance to said force.

It is manifest that should a force be applied to any one of the spring members 15, 16, 17 or 18 that the coiled springs 25 will be compressed and be caused to act in a manner similar to a solid bar and transmit the force applied to the spring member at one end of the coiled spring to the spring member provided at the opposite end thereof.

To facilitate this last named function of the coiled springs 25, they may be enclosed in a tubular flexible casing 27 which may be of rubber, fabric or any other suitable material which will allow the coiled spring 25 to expand and contract upon the application and release of said force, and will also aid in reducing the injury to another vehicle or other object with which the bumper engages.

It is evident that a bumper may be composed of one or a plurality of members such as 20 and 21. If a bumper having a plurality of members 20 and 21 is preferred these will be connected together by the members generally designated 28 which extend from one member to the other across the opening or space existing between said members 20 and 21, and prevent the passage of an object between said last mentioned members. The cross members may be of a flexible character as illustrated in Figures 1 and 2 or may be of a more rigid character as shown in Figure 7. The cross members 28 illustrated in Figures 1 and 2 are composed of 105 clips 29-29 which are located at suitable intervals throughout the length of the members 20 and 21, are securely fastened thereto and have the chain sections 30 fastened to said clips, the said chain sections being extended transversely across the space produced between said members 20 and 21.

It is manifest that should a force be applied to one or both of the members 20 and 21 that the initial action of said force will 115 be resisted by the coiled spring 25 and also to some extent by the spring elements 15 to 18.

It is further evident that should the force exceed the prescribed resistance of said 120 spring that this excess will be applied to the chain or other similar element confined within said spring and thereafter be transmitted and resisted by the pairs of elements designated 15 to 18.

125 The structure illustrated in Figures 3 to 6 employs a spring, chain or other flexible element similar to the structure illustrated in Figures 1-2, but differs in the connections whereby these portions are attached to

the frame or chassis of the vehicle and therefore, the construction of the member 31 will not again be explained in detail. In the structure illustrated in Figures 3 to 6 pivoted 5 nonresilient members 32 and 33 are employed for attaching said member 31 to the chassis. These members 32 and 33 are respectively pivotally connected at 34 and 35 to the frame of the vehicle by means of the 10 brackets 36 which are securely fastened to the chassis of the vehicle. These members 32 and 33 each include an arm 37—which has one end secured to a bracket 36 and has a plurality of leaf spring members 38, 39 and 15 40 attached to the opposite end. The spring member 39 is interposed between the spring members 38 and 40, is curved outwardly relatively to the end of the vehicle and extends sidewise a sufficient distance to protect the 20 vehicle to which it is attached. Each of these members 39 is provided with a plate designated 41, which is of a substantial width and provides a guard at this portion of the structure. This plate 41 is designed 25 to permit the attachment of the members 31 thereto as clearly shown in Figures 3 and 6.

When the parts of the bumper assume a normal position as illustrated in full lines in Figure 3, the action of the spring member 31, 30 upon the members 32 and 33 is limited by the stops 42 and 43 which respectively engage and limit the inward movement of said members, but permit the outward movement thereof as illustrated in dotted lines in Figure 3.

By virtue of the flexible element or chain confined within the member 31 this outward movement will also be limited, however, should a force be applied to either of the pivoted members 32 or 33 sufficient to bring the flexible element into action. This additional or excess force will be resiliently resisted by the other of the yieldable pivoted elements generally designated 32 and 33 45 which will thus prevent breakage of the bumper and reduces to a minimum the possibility of injury to an object with which the bumper contacts.

In Figures 8, 9 and 10 a bumper is disclosed which is provided with an element for protecting the end of the bumper and which will also reduce the injury resulting to and from its engagement with another object. It is of course understood that this feature can be applied to bumper structures other than those disclosed herein. The particular construction illustrated contemplates the use of a suitably shaped armor plate which is applicable to be associated with and secured to a bumper at the juncture of the means whereby said bumper structure is mounted or secured to the chassis of the vehicle and the members which extend across the end of the vehicle.

60 65 This armor is designated 44 and is formed

so as to provide a protecting shell which extends from a point adjacent the uppermost portion of the upper cross member to below the lowermost portion of the lower cross member, and in addition extends sidewise to 70 beyond the outermost portion of the spring elements whereby the bumper structure is secured to the vehicle.

This shell 44 is preferably curved both vertically and horizontally and therefore 75 will present an oblique surface to an object and strike a glancing instead of a direct blow which will reduce the possibility of injury to both objects.

As clearly shown in Figure 9, this armor plate is secured to a support 45 and extends laterally therefrom so that it may protect the resilient elements whereby the bumper is secured to the vehicle, the armor being formed so that freedom of movement of said 80 resilient members may result.

In the modified structure illustrated in Figure 12 the use of a flat coiled spring 46 is contemplated, which may be substituted for the cross members illustrated in Figures 1 to 5. The spring member such as 46 is of a substantial width which will thus eliminate the necessity of the use of one of the coiled spring members above referred to. The member 46 is secured to the leaf spring 47 whereby the structure is secured to the vehicle by means of a plate 48 which is bolted or otherwise secured to the spring and has the enlarged portion 49 which is enclosed within the tapering interior of the flat coil spring 46. This portion of the plate 48 is apertured and has an end of the chains 50—51 secured to it, the latter chain members being employed to provide a means for limiting the expansion of the spring and to be substituted therefor to resist those forces applied to the spring which are in excess of the predetermined resistance of the spring.

The structure illustrated in Figure 11 discloses another means whereby the bumper 110 may be connected to the chassis of the vehicle. In this structure the yieldable members or springs such as 16 to 18 are connected so as to permit them to pivot at 54, the extremity of said members being secured to 115 the chassis by the clip or clevis 55.

From the foregoing explanation of the construction and operation of the various embodiments of the invention illustrated in the drawings, it is manifest that a construction is provided in which the elements employed co-act with each other to resist various forces applied to the structure.

It is further evident that an efficient structure is produced whereby the ends of the bumper are protected against the possibility of injury which does not interfere with the operation of the portions protected thereby.

Having thus described the invention what 130

I claim and desire to cover by Letters Patent is:

1. In an automobile bumper the combination of a member which extends across the end of the vehicle, members whereby said first mentioned member is secured to the vehicle, said member including means which will yieldably resist an initial predetermined force applied to the bumper and yieldable flexible means operable to relieve said first mentioned yieldable means and to resist said force after said predetermined force has been reached.

2. In an automobile bumper the combination of a member which extends across the end of a vehicle, members whereby said first mentioned member is secured to the vehicle, said member which extends across the vehicle including means which will yieldably resist an initial predetermined force applied to the bumper and extensible means operable to be subsequently brought into action to assist said first mentioned yieldable means and to resist said force after said predetermined force has been reached.

3. In an automobile bumper the combination of a member which extends across the end of a vehicle, members whereby said first mentioned member is attached to the vehicle, said member which extends across the vehicle including means which will yieldably resist a predetermined force and including an element which also extends across the vehicle and which is operable to relieve said means and resist said force.

4. In an automobile bumper the combination of a member which extends across the end of a vehicle, members whereby said first mentioned member is attached to the vehicle, said member which extends across the vehicle being expansible and having associated therewith a means which is extensible and operable to limit the expansion of said expansible member.

5. In an automobile bumper the combination of a member which extends across the end of a vehicle, members whereby said first mentioned member is attached to the vehicle, said member which extends across the vehicle being expansible and having associated therewith a means which is extensible and operable to limit the expansion of said expansible member, and means associated with the extensible member for resiliently resisting the force applied thereto.

6. In an automobile bumper the combination of means whereby said bumper may be attached to a vehicle and a coiled spring member which is attached to said means and extends across the end of said vehicle, said member being permitted to expand upon contacting with an object and to contract when said contact is released.

7. In an automobile bumper the combination of means whereby said bumper may

be attached to a vehicle, and a coiled spring member which is attached to said means and extends across the end of said vehicle, said coiled spring member being permitted to expand upon contacting with an object and to contract when said contact is released, and means for limiting the expansion of said member.

8. In an automobile bumper the combination of means whereby said bumper may be attached to a vehicle and a pair of members which are attached to said means, said members being arranged parallelly to each other and having connectors which connect said parallel members together, said members being permitted to expand and contract upon contact and release of an object by said bumper.

9. In an automobile bumper the combination of yieldable means whereby said bumper may be attached to a vehicle and an expansible and contractable member which extends across the end of the vehicle connected to said yieldable means.

10. In an automobile bumper the combination of a member which extends across the end of the vehicle, members whereby said first mentioned member is attached to the vehicle, said member which extends across the vehicle including means which are expansible to yieldably resist a predetermined force and including an element which is operable to relieve said means and resist said force.

11. In an automobile bumper the combination of a member which extends across the end of a vehicle, members whereby said first mentioned member is attached to the vehicle, said member which extends across the vehicle being expansible and having associated therewith a means which is extensible and operable to limit the expansion of said expansible member and means for limiting the extension of said means.

12. In an automobile bumper the combination of means which extend outwardly with respect to the vehicle whereby said bumper may be attached to a vehicle, a spring the opposite ends of which are respectively attached to each of said means, and said spring being permitted to expand upon contact with an object and be resisted by said means.

13. In an automobile bumper the combination of means which extends outwardly with respect to the vehicle, whereby said bumper may be attached to a vehicle and a member which is attached at its opposite ends to said means and extends across the end of said vehicle, said member being permitted to expand upon contacting with an object and to contract when said contact is released, and means also attached at its opposite ends to said first mentioned means for limiting the expansion of said member.

14. In an automobile bumper the com-

5 combination of forwardly extending members pivoted to swing outwardly and means for preventing inward bodily movement thereof upon said pivots, and a member supported by said first mentioned pivoted members, said last mentioned member being expandable upon the application of a force applied thereto.

10 15. In an automobile bumper the combination of pivoted yieldable means whereby said bumper may be attached to a vehicle and an expansible and contractable member which extends across the end of the vehicle connected to said pivoted yieldable means and means for limiting the expansion of said member.

20 16. In an automobile bumper the combination of yieldable means whereby said bumper may be attached to a vehicle and an expansible and contractable member which extends across the end of the vehicle connected to said yieldable means and means for limiting the expansion of said member and the movement of said yieldable means.

25 17. In an automobile bumper the combination of means whereby said bumper may be attached to a vehicle, a member secured to said means and being extended across the end of the vehicle, said member being expandable upon the application of a force applied thereto, and means extended lengthwise of the expansible member for limiting the expansion of said member, said means being operable to resist the force applied 30 to said member.

35 40 18. In an automobile bumper the combination of means whereby said bumper may be attached to a vehicle, said means being yieldable and having means secured thereto which extends across the end of the vehicle, said last mentioned means being expandable upon the application of a force applied thereto, and means located within the second mentioned means for limiting the 45 expansion of said member, said last mentioned means being operable to resist the force applied to said member.

50 55 19. In a bumper the combination of forwardly extending supporting members and guard members arranged crosswise and laterally of said supporting members and a plate providing a shield, said plate being arranged to extend along adjacent the end of the cross member and along said laterally arranged guard member.

60 65 20. In an automobile bumper the combination of means whereby said bumper may be attached to a vehicle and an expansible member attached thereto which extends across the end of said vehicle, means for limiting the expansion of said member and a casing for enclosing said expansible member and last mentioned means.

65 21. In an automobile bumper the combination of means whereby said bumper may

be attached to a vehicle and an expansible member attached thereto which extends across the end of said vehicle, means for limiting the expansion of said member, a casing for enclosing said expansible member and last mentioned means, and a guard provided at the juncture of said first mentioned means and the expansible member.

70 75 22. An automobile bumper having a forwardly extending member located at each side of the vehicle said member being pivotally fixed adjacent an end to the vehicle and having an end which is movable toward the side of said vehicle and means acting upon said forwardly extending member for restoring said member from said last mentioned position.

80 85 23. In an automobile bumper the combination of forwardly extending members pivoted to swing outwardly and means for preventing bodily inward movement thereof upon said pivots, and a member supported by said first mentioned pivoted members said last mentioned member being expandable upon the application of a force applied thereto and being extensible upon the outward movement of said pivoted members.

90 95 24. In an automobile bumper the combination of forwardly extending members pivoted to swing outwardly and means for preventing inward bodily movement thereof upon said pivots, and a member supported by said first mentioned pivoted members, said last mentioned member being expandable upon the application of a force applied thereto and means for limiting the expansion of said expansible member.

100 105 25. In an automobile bumper the combination of forwardly extending members pivoted to swing outwardly and means for preventing bodily inward movement thereof upon said pivots, and a member supported by said first mentioned pivoted members said last mentioned member being expandable upon the application of a force applied thereto and being extensible upon the outward movement of said pivoted members and means for limiting the extension of said expansible member.

110 115 26. In an automobile bumper the combination of forwardly extending members pivoted to swing outwardly and means for preventing bodily inward movement thereof upon said pivots, said pivoted members providing supports for a member, which is extensible upon the outward movement of said pivoted members and means for limiting the extension of said extensible member.

120 125 27. In a bumper the combination of forwardly extending supporting members and guard members arranged crosswise and laterally of said supporting members and a plate providing a shield, said plate being arranged to extend along adjacent the end of the cross member and along said laterally

arranged guard member, said plate being curved lengthwise and transverse of its length.

28. A bumper comprising a longitudinally expansible impact member, and pivotally mounted supporting arms connected to opposite ends of the impact member, said supporting arms having portions lying outwardly beyond the pivots of the arms so that said outwardly extending portions may move rearwardly and expand the impact member when impinging an object.

29. A bumper comprising a longitudinally expansible and laterally flexible impact member, and supporting arms, each having an abutment for limiting the movement of the arm in one direction, said abutment being held in abutting position by the impact member and being movable away from abutting position when the supporting arm is engaged to expand the impact member.

In witness whereof, I hereunto subscribe my name this 22nd day of May A. D., 1923.

HELGE A. BØRRESEN.
